CAPSULE SHAKER NEST

Alvin A. Greenberg, Baltimore, Md.

Application December 2, 1947, Serial No. 789,175

3 Claims. (Cl. 259—72)

1

This invention relates to agitators for ampules, capsules or other small containers in which ingredients are enclosed and require shaking, mixing or compounding before being used, and more particularly to a holder for sustaining several plural capsules at a time suitable for placement on an agitator designed to shake such items violently.

In a particular form of device of the prior art, an agitator is employed for oscillating a single capsule or the like so its contents will be mixed together. The agitating mechanism is operated by a motor, on the shaft of which is provided an eccentric element supporting a holder for capsules. The holder is resiliently suspended from the base of the motor. The mechanism gives the holder a vibratory or oscillating movement that ordinarily shakes the capsule in a horizontal direction. The capsule is inserted directly into the holder, and this device has the disadvantage of being limited to the use of one ampule or capsule. Where the quantity or ingredients in a single capsule is insufficient for a particular purpose, the agitator has to be used several times. This involves time and effort and is not desirable in many instances as it usually will materially affect the condition of the product and perhaps render it unfit for the particular purpose for which it is to be used. It is therefore the purpose of this invention to provide an adjunct to the holder mentioned that will enable several capsules to be held therein and shaken at the same time and avoid one or more of the disadvantages and limitations of the prior art.

Another object of the invention is to provide a new and improved casing for holding several capsules at a time and for removably attaching same to the holder of an agitator that will be able to shake them all at the same time and in the same manner.

An additional object of the present invention is to provide a new and improved casing for holding several capsules in the holder of an agitator so they will be manipulated at the same time therein and can be removed (or replaced) as a unit for use or agitation, and their contents mixed up or compounded, in an expeditious, convenient and effective manner.

In order to make the principles and objects of this invention clearer, reference is made to the appended drawings. These drawings indicate a particular form of the invention by way of example, and their details are explained in the description following, while the claims particularly emphasize the scope of the invention.

- 5 In the drawings:
- Figure 1 is a view in elevation of a casing for capsules embodying this invention, and shown held by an agitator;
- 10 Figure 2 is a plan view of the casing shown in Figure 1;
- Figure 3 is a side elevation of Figure 2; and
- 15 Figure 4 is a plan view of a modified form, with portions broken away to indicate the interior construction;
- Similar reference characters refer to the same parts throughout the drawings.
- In the particular structure shown in the drawings, a lower section 11 of a capsule casing 10 is provided with a three-fold series of depressions 12 in which capsules 13 may be set and held. The walls of the section 11 encompass the capsules 13 closely on half of the sides as indicated in Figure 2.
- 20 An upper section 21 with depressions 22 symmetrical with those of the lower section 11 serves to cover the capsules 13 and hold them in the casing. The sections 11 and 21 are hinged together at one end and are clamped together at the opposite end by a clamp 23 extending transversely across the casing, as shown. This clamp 23 is locked together by the resilient engagement of its end portions 24 formed to hook on each other. The sections 11 and 21 are constructed with intervening webs 25 between the depression portions to make the structure of the casing more compact and easier to handle. The ends of the center section are rounded to form a pair of hemispherical caps 16 which can be held by clips 17 on the holder 18 of an agitator 19.
- 25 This agitator operates with a motor 26 on which an oscillating mechanism 20 is mounted. This mechanism causes the holder 18 to swing backwards and forwards and employs a coil spring 30 by 35
- 35 This agitator operates with a motor 26 on which an oscillating mechanism 20 is mounted. This mechanism causes the holder 18 to swing backwards and forwards and employs a coil spring 40 by 45
- 40 Since the casing holds three capsules, it has sufficient capacity to handle a large quantity of ingredients and resulting products. This is possible through the placement of the casing in the clips that previously held only a single capsule. This expands the use of the holder and makes it practical to shake a plurality of capsules.

In the modified form shown in Figure 4 the casing 30 is made in a hollow shape not separable into half sections, but separable into sections 31 and 32 which serve as a body and cap respect-

tively. The hollow interior of the section 31 has three depressional formations 33 that serve to hold the capsules 13 therein, the cap 32 is provided with tapered counterbored portions 48 which fit over the tapered ends 41 of the hollow interior sections 31 and prevent the capsules 13 from coming out when the cap is put on. The formations 33 are joined by webs 34 that serve to keep them spaced apart. The cap 32 is held to the ends 41 by friction and by the spring clips 17 of the shaker pressing thereon. The projections 36 secured to the cap 32 and the section 31 of the casing 30 are of adequate size and form to fit into the clip 17 provided on the holder 18. When in these clips and under the oscillating action of the holder, the casing will be shaken so the contents of the capsules 13 will be mixed or compounded as required.

While but several general forms of the invention are shown in the drawings and described in the specification it is not desired to limit this application for patent to these particular forms, as it is appreciated that other forms could be made that would use the same principles and come within the scope of the appended claims.

Having thus described the invention, what is claimed is:

1. A container for capsules comprising two casing sections, said sections having a plurality of internal co-axial depressions therein adapted to house the capsules, co-acting closure means for said casing sections, and external symmetrical extensions carried by each of said casing sections midway of the longitudinal confines thereof, and athwart said closure means, and adapted to fit into the holding clips of a shaker.

2. A container for capsules comprising two casing sections, a hinge connecting said sections at one end, and spring means connecting the opposite end, said sections having a plurality of internal co-axial depressions therein adapted to house the capsules, and external symmetrical extensions carried by each of said casing sections, athwart said connecting means, and adapted to fit into the holding clips of a shaker.

3. A container for capsules comprising two casing sections, one of said sections having tapered projections and the other section having complementary counterbored portions to receive said tapered projections and to frictionally retain them, whereby to secure said casing sections together, said sections also having a plurality of internal co-axial depressions therein to house the capsules, and external symmetrical extensions carried by each of said casing sections, athwart said securing means between the sections, and adapted to abut against and frictionally engage the holding clips of a shaker.
